US00D692893S

(12) **United States Design Patent**
Wesolek

(10) **Patent No.:** **US D692,893 S**
(45) **Date of Patent:** **** Nov. 5, 2013**

(54) **ELECTRONIC DEVICE**(75) Inventor: **Bryan J. Wesolek**, Laporte, IN (US)(73) Assignee: **Data Ltd., Inc.**, LaPorte, IN (US)(**) Term: **14 Years**(21) Appl. No.: **29/419,442**(22) Filed: **Apr. 27, 2012**(51) **LOC (9) Cl.** **14-02**(52) **U.S. Cl.**USPC ..... **D14/429**; D14/426(58) **Field of Classification Search**

Primary Examiner — Susan Moon Lee(74) *Attorney, Agent, or Firm* — Stites & Harbison PLLC; Juan Carlos A. Marquez, Esq.(57) **CLAIM**

The ornamental design for an electronic device, as shown described.

DESCRIPTION

FIG. 1 is a front perspective view of an electronic device showing my new design;

FIG. 2 is a rear perspective view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a top plan view thereof; and,

FIG. 8 is a bottom plan view thereof.

Broken lines and unshaded portions contained within broken lines are not claimed.

1 Claim, 5 Drawing Sheets(56)
